FIG. - 1

FIG. - 2

INVENTOR

CHRISTIAN A. RASMUSSEN

BY Fisher, moore moore.
ATTORNEY

UNITED STATES PATENT OFFICE

CHRISTIAN A. RASMUSSEN, OF CLEVELAND, OHIO

SPRING

Application filed April 27, 1931. Serial No. 533,047.

My invention relates to an improvement in electrical controllers and more particularly to contact devices for controllers of the rotatable drum type, and my object in general 5 is to provide a simple, inexpensive, and durable contact device, which may be readily installed in close and compact relation with other co-acting contact parts, and which may be easily assembled and dis-assembled for 10 convenient inspection, removal and replacement of the parts subject to the greatest wear, all as hereinafter shown and described and more concisely set forth in the claims.

In the accompanying drawing, Fig. 1 is a 15 side elevation of a set of my improved contact devices or fingers assembled to be installed opposite a rotatable switch drum of an electrical controller and Fig. 2 is a front elevation of Fig. 1. Figs. 3 and 4 are plan 20 and side elevations respectively of the resilient means provided for retaining the contact member in position on the base, and Fig. 5 is a fragmentary side elevation of the resilient means and locking member showing the mode 25 of dis-assembling the resilient means from its locking member.

Referring now to the drawing, the present 30 contact device comprises a main body or supporting member A, made in two parts 2 and 3, tightly clamped together by a screw 5. Both parts 2 and 3 are provided with recessed oppositely arranged seats 6 to grip insulated and round supporting rods 7 for securing the contact device in its proper working position 35 and part 3 is formed with a bent extremity 5 adapted to serve as a stop or abutment for a set screw 6', carried by a movable contact finger 9, which rests at its rear end upon an elevated flat inclined seat 7' and abuts against 40 an inclined thrust shoulder or extension 8 formed on the rear end of part 3. Finger 9 is composed of two flat strips or pieces riveted together, and the base piece 10 is made of heavier stock than the superposed strip 11. 45 Preferably strip 11 is made of copper for better conductivity of the electric current, which is conveyed thereto from part 3 of supporting member A by short laminated strips D of copper secured at one end by bolt 12 to 50 part 2 and at its other end by a screw 14 to

finger 9. Finger 9 may turn or pivot on inclined seat 7' and the short extension 8, laminated copper strips D preventing it from being displaced or disconnected. In addition, a flat post 15 projecting through a slot 55 16 formed in the parts composing finger 9 prevents displacement of finger 9 and also serves as a mounting for a short helically coiled compression spring 18 which seats 60 upon finger 9 and encircles post 15.

The post 15 is formed of a flat piece of steel 65 having a short stem 19 which projects at one end through a square opening in part 2 of supporting member A, and is securely fastened against turning by upsetting or riveting. The other end of the post tapers in width and has a hook-shaped head 20 adapted to interlock with coiled compression 70 spring 18, so that spring 18 applies a yielding pressure to finger 9 to hold the contact tip 21 against a switch drum (not shown) when the latter is rotated in respect thereto. Thus, the upper uncoiled wire end of helical 75 spring 18 is sharply bent downwardly and upwardly to form a depending loop-shaped portion or member 22 within the convolutions of the spring. Member 22 is approximately half the length of spring 18, when the latter is not under compression and includes two parallel arms 23 and 24, connected at their lower ends by the bridge or cross 80 piece 25 of the loop. The free arm 24 of member 22 is sharply bent downwardly to form a short hook 27 for engagement with the upper convolution of spring 18, when the latter is seated upon finger 9 and coupled with head 20 of post 15, thus insuring axial alignment of loop-shaped member 22 and 85 spring 18 under all conditions.

The described shape and form of spring 90 member 18 and its looped member 22 permits of ready attachment or detachment thereof during assembly and disassembly of my contact device. To assemble, finger 9 is sleeved over head 20, and the open end of spring 18 is sleeved upon head 20 in such a position that when the spring is manually compressed, bridge 25 will readily engage with the recessed or hook portion of head 20. Upon 95 release of pressure the spring 18 will expand 100

and cause the parts to interlock. In dis-assembling operations spring 18 and head 20 are disconnected by local pressure applied to one side of the upper coil of spring 18, which creates buckling of the coil, under which hook member 22 has a tendency to move away from the recessed portion of head 20, as clearly disclosed in Fig. 5 of the drawing.

Strip 11 is slightly offset from base strip 10 at its outer extremities to provide a seat for the flat extension 26 of copper contact tip 21, a screw 40 being employed to connect the extension tightly between the ends of the strips. A bent spring 27' riveted to contact finger 9 adjacent the set screw 6' serves to lock this set screw against accidental turning after proper adjustment has been made. A lug 29 for attaching a terminal member to body A is secured to extension 28 of member 20 A by screw-bolt 12.

It will be obvious that the spring 18 may be advantageously employed for effecting yielding connection between any co-operating parts which are pivotally interlocked with each other or are parallelly movable with respect to each other, and therefore I do not wish to restrict the use of such spring and its co-operating hook member to the particular switch arrangement disclosed.

What I claim, is:

1. As an article of manufacture adapted to yieldingly connect a series of members having partly intersleeved portions, a compression spring seated upon one of said portions and partly sleeved over the other of said portions, said spring including integral, freely and laterally shiftable locking means extending from one end of said spring into its hollow portion to the center thereof for readily reusable engagement with that portion over which it is sleeved.

2. As an article of manufacture for yieldingly connecting partly intersleeved members, a compression spring comprising a main spring body and an integral elongated loop of less width than the interior diameter of said spring, extending from one end of said spring axially into its main body to the center thereof.

3. As an article of manufacture for yieldingly connecting partly intersleeved members, a compression spring comprising a main body having an integral elongated loop portion of substantial less width than the interior diameter of said spring and formed with parallel leg portions downwardly extending into the body of the spring to the center thereof, one of said leg portions being hooked to the upper coil thereof for axial alignment with the main body of said spring.

In testimony whereof I affix my signature.
CHRISTIAN A. RASMUSSEN.
